UNITED STATES PATENT OFFICE.

NILES C. TOLL, OF LATHROP, CALIFORNIA.

DISAPPEARING FOLDING CASTER.

1,022,646.

Specification of Letters Patent.

Patented Apr. 9, 1912.

Application filed May 20, 1911. Serial No. 628,531.

To all whom it may concern:

Be it known that I, NILES C. TOLL, a citizen of the United States, residing at Lathrop, in the county of San Joaquin, State 5 of California, have invented certain new and useful Improvements in Disappearing Folding Casters; and I do declare the following to be a full, clear, and exact description of the same, such as will enable others 10 skilled in the art to which it appertains to make and use the same, reference being had to the accompanying drawings, and to the characters of reference marked thereon, which form a part of this application.

15 This invention relates to improvements in furniture and particularly to the casters used in tables, chairs and the like, the object of the invention being to produce a caster which can be made to disappear into the 20 leg of the furniture when the furniture is stationary, but which can readily be projected out from the leg when it is desired to move the furniture at any point.

A further object of the invention is to 25 produce a simple and inexpensive device, and yet one which will be exceedingly effective for the purposes for which it is designed.

These objects I accomplish by means of 30 such structure and relative arrangement of parts as will fully appear by a perusal of the following specification and claims.

In the drawings similar characters of reference indicate corresponding parts in the 35 several views.

Figure 1 is a side elevation of a table partly broken out, showing my improved mechanism. Fig. 2 is a sectional view of a leg of a table showing my improved caster 40 mechanism therein. Fig. 3 is a sectional view of a tubular member adapted to be inserted in the leg of the table to carry my improved caster mechanism. Fig. 4 is a view of the under side of a portion of a 45 table showing a caster operating drum and other structure.

Referring now more particularly to the characters of reference on the drawings, 1 designates a table or other piece of furniture 50 and 2 the legs thereof. In using my improved device each leg is provided with an interior recess 3 into which is fitted a tubular member 4, there being a slot 5 projecting upwardly through the leg from the recess 3 and having a pulley 6 in its upper end.

The numeral 7 designates a solid cylindrical member movable vertically in the member 4 and rotatably mounted on a rod 8 having an upwardly projecting arm 9, said arm 9 having a vertical slot 10 through 60 which projects a pin 11 secured in the sides of the member 4 and carrying rollers or pulleys 12. A cable 13 is secured to the upper end of the arm 9 and projects downwardly over the rollers 12 and then projects 65 upwardly through the slot 5 over the roller or pulley 6 and thence around a drum 14 journaled in the under side of the table, which is the common drum around which each cable from the various legs of the furniture extends, whereby they may all be operated at once as may hereinafter appear.

On the under side of each member 7 is hinged a caster 15 adapted to fit within the 75 member 4.

When it is desired to use the casters, the same are projected without the member 4 by means of the following structure, namely: An operating handle member 16 fits into the drum 14 in such a manner that when it 80 is desired to project the casters outside of the legs for the purpose of moving the furniture, then this handle member 16 may be pulled out to operating position as shown by dotted lines in Fig. 4 and the drum 14 85 rotated, whereby the cables 13 will be wound up, which pulls the arms 9 and incidentally the members 7 and casters 15 downwardly, which will project the casters outside of the members 4 and incidentally of the legs 2. 90 The casters 15 are provided with lugs 17 which project against the member 7 and prevent the casters from bending the wrong way, and hence this drives the caster into folded position against the member 7, there 95 being a hole 18 in each caster adapted to receive a pin 19 on the member 7, whereby the caster is held in fixed proper position.

On one end of the drum 14 is a ratchet wheel 20, engaged by a spring pressed dog 21, whereby the cables can not unwind until it is desired to unwind them and retract the casters 15 back into the members 4, then a handle 22 is employed to disengage the ratchet dog 21 from the wheel 20, and then the weight of the table forces the casters back into the members 4 and leaves the table legs stationary upon the floor surface, as shown in Figs. 1 and 2.

When the casters turn with the movement 110

of the furniture the members 7 are the ones which permit the turning movement by reason of their being rotatably mounted on the members 8, and hence the members 8 and 5 arms 9 remain in fixed vertical position by reason of the pin 11 disposed through the slots 10, and hence the cables are kept from becoming twisted or entangled.

From the foregoing description it will 10 readily appear that I have produced such a device as substantially fulfills the objects of the invention as set forth herein.

While this specification sets forth in detail the present and preferred construction 15 of the device, still in practice such deviations from such detail may be resorted to as do not form a departure from the spirit of the invention.

Having thus described my invention what 20 I claim as new and useful and desire to secure by Letters Patent is:—

1. A member having a recess on its under side, a member movable vertically in said recess, a caster comprising a yoke carrying a 25 wheel, such yoke being hinged to said movable member, such yoke being provided with a hole disposed independently of its hinged

relation to said movable member, and a pin on said member adapted to fit into said hole.

2. A device of the character described 30 comprising a member having a recess in its under side, a member movable vertically in said recess, an upwardly projecting arm on said movable member, a pin secured in said movable member, rollers on said pin, a cable 35 secured to the upper end of said arm and projecting over said rollers, means for winding said cable and a caster comprising a yoke carrying a wheel, such yoke being secured to said movable member, as described.

3. A member having a recess in its under side, a member movable vertically in said recess, a caster comprising a yoke carrying a wheel, such yoke being hinged to 40 said member and a projecting stop member on the upper end of said yoke adapted to engage said movable member to limit the hinged movement of said yoke as described.

In testimony whereof I affix my signature in presence of two witnesses.

NILES C. TOLL.
